UNITED STATES PATENT OFFICE.

FLOYD F. FLINT, OF DETROIT, MICHIGAN. ASSIGNOR OF ONE-HALF TO MAXWELL W. BENJAMIN, OF DETROIT, MICHIGAN.

CARBURETOR.

Application filed October 29, 1923. Serial No. 671,504.

To all whom it may concern:

Be it known that FLOYD F. FLINT, citizen of the United States, residing at Detroit, in the county of Wayne and State of Michigan, ⁵ has invented certain new and useful Improvements in Carburetors, of which the following is a specification.

This invention relates to carburetors such as are used in connection with automobiles ¹⁰ and other internal combustion engines.

More particularly the invention relates to means for supplying liquid fuel to a carburetor.

Heretofore it has been common to provide ¹⁵ a fuel supply to carburetors from a tank lower than the instrument by suction produced in a chamber interposing between the carburetor proper and the fuel supply tank. It has also been the common practice to utilize ²⁰ the suction of the engine for the purpose of producing a partial vacuum in the intermediate chamber and thus raise the fuel from the fuel tank by atmospheric pressure.

²⁵ This method of operation, while quite well known, is open to serious objections. In the first place there is necessarily required an extra tank or chamber and the connections thereof are quite complicated in their nature.

One important object of the present invention is to provide an improved form of fuel feed for carburetors wherein the use of an auxiliary or intermediate chamber may, ³⁵ if desired, be entirely disposed with.

A second important object of the invention is to provide an improved fuel feed of this class wherein the connection between the supply tank and carburetor may be a simple pipe line with the valves or other parts between the tank and the carburetor thus eliminating the complicated pipe system necessary with the usual vacuum tank.

In the ordinary vacuum tank feed other ⁴⁵ objections exist by reason of the fact that it is not possible when using the vacuum effect produced by the engine operation, to control in a proper manner the suction for lifting the fuel, since changes in the operating condition of the engine cause such suction to vary within extremely wide limits.

A third important object of the invention is to provide an improved arrangement of

fuel feed which will be independent of the suction produced by the engine operation. ⁵⁵

A still further objection that exists in the present system is that such system is applied directly to a carburetor and it is necessary to have the suction pipe from the fuel receiving chamber closed off at intervals from ⁶⁰ the source of suction in order to permit flow of the fuel from the chamber to the jet nozzle. When this is done under the present arrangement it will happen that the valve will not open at the proper time and consequently as soon as the fuel has been exhausted from the receiving chamber the engine will stop. ⁶⁵

A fourth object of the invention is to provide an improved fuel feed having a relief valve means whereby the valve control in the connection between the fuel receiving tank and the carburetor will be properly operated at all times and under all conditions of engine operation. ⁷⁵

A fifth important object of the invention is to provide a fuel feeding means wherein the fuel is delivered by a special form of pump particularly adapted for use in this connection. ⁸⁰

A sixth important object of the invention is to provide a novel construction in the pump itself.

With the above and other objects in view as will be hereinafter apparent, the invention consists in general of certain novel details of construction and combinations of parts hereinafter fully described, illustrated in the accompanying drawings and specifically claimed. ⁸⁵

In the accompanying drawings like characters of reference indicate like parts in the several views, and:

Figure 1 is a side elevational view partly in section of a carburetor especially adapted ⁹⁵ for use in connection with this invention.

Figure 2 is a plan view thereof.

Figure 3 is a horizontal section thereof and a special form of the pump used herewith. ¹⁰⁰

Figure 4 is a side elevation of such pump.

Figure 5 is a section on the line 5—5 of Figure 3.

Figure 6 is a section on the line 6—6 of Figure 3. ¹⁰⁵

Figure 7 is a diagrammatical view show-

ing the arrangement of the carburetor and pump in connection with the ordinary fuel tank.

Figure 8 is a similar view showing the use of an intermediate vacuum chamber in connection with this arrangement.

The present embodiment of the invention, as shown in the drawings, illustrates one preferred form thereof, but it will be understood that the principles involved may assume in actual practice, a variety of forms, and this embodiment is to be understood as merely to show one of such forms, the invention not being confined to the particular 10 form and proportions herein illustrated.

In this embodiment there is provided a hollow bottom 10 constituting a reservoir. This bottom is of elongated form and at one end thereof there is superimposed on the 20 bottom a float chamber 11. This float chamber 11 consists of a cylindrical tube 12 forming the side wall thereof, this tube being seated on a gasket 13 and having a top 14 closing the upper end. The tube is held on the gasket and the top of the tube by means of suitable studs 15, which extend through the top and into the top of the reservoir 10. The top of the reservoir 10 is provided, centrally of the tube 12, with an opening 16 wherein is seated a housing 17 having a valve casing 18 projecting from one side. In this valve casing is fitted a poppet valve 19 which opens from the chamber 11 inwardly to the reservoir 10 at certain times 30 during the operation and closes communication between the float chamber and reservoir at other times. Located centrally of the housing 17 and depending from the top thereof is a valve stem guide 20, the lower 40 end of the vertically movable valve stem 21 having fixed thereon a lower collar 22, and an upper collar 23 in spaced relation. Above the upper collar 23, the valve stem carries a valve 24 which serves to close the lower 45 end of a suction pipe 25 screwed through the top 14. Screwed into one side of the top is a pipe T 26 having its upper end closed normally by a plug 27. To this pipe T is connected a casting 28 containing a downwardly opening relief valve 29 of ordinary and well known construction. Intermediate the ends of the T a branch pipe or conduit 30 leads to a pump indicated in general at P. Similarly there is provided for the gasket 50 a supply conduit 31 which may lead directly to the supply tank T as shown in Figure 7 or to an intermediate vacuum chamber 32 in which case the pipe 30, instead of being connected to the top of the float chamber as just described, will be connected with its relief valve 29, to the top of the vacuum chamber 32. However, it is preferred to use the form shown in Figure 7 since with this form the invention is adapted for employment with 60 any of the well known forms of carburetor

without any changes whatever in the jet nozzle and venturi arrangements.

At 33 is the float and opening into the housing 17 is a vent tube 34 which passes downward through the float, as shown in Figure 1, and is provided at its upper end with a slight clearance, as shown at 35. By this arrangement a proper admission and exhaust of air is permitted in the lower and upper chambers.

The carbureting portion of the device is indicated in general at C and since the specific construction of this part of the device forms no portion of the present invention it will not be described in detail.

With respect to the pump P, I have found that neither the ordinary type of reciprocating pump nor a rotary pump will serve to effect proper vacuum conditions in the apparatus. There has accordingly been provided a special form of oscillating pump, which has the advantage of producing in a prescribed manner the desired vacuum conditions and which also is inherently so constructed as to be noiseless in operation and self-lubricating. To this end there is mounted on a suitable support, which may be a part of the engine, a bracket 36 having a leg 37, which is preferably arranged in a vertical position. Through this leg 37 extends an opening 38 and journalled in this opening is a pivot shaft 39 supporting an oscillating cylinder 40. The shaft projects laterally from the central part of the cylinder and the cylinder is provided with a flat side 41 bearing against the inner side of the leg 37 or plate 36. Surrounding the shaft 39 is a spring 42 which bears at one end against the leg 37 and at its other end against a washer 43 held on the shaft by a nut 44. By this means the cylinder is held firmly pressed against the plate 41 but may yield sufficiently to permit lubrication of the contact surface. In the plate 37 is provided an exhaust port 45 and inlet port 46 to which the conduit 30 is connected. Cooperating with these ports is a port 47 which leads from the flat side of the cylinder to its interior and is so positioned that oscillation of the cylinder causes the port 47 to register alternately with the ports 45 and 46. Mounted reciprocally in the cylinder is a piston 48 which moves between the dotted line position, shown in Figure 3, and the full line position, shown in that figure. It 100 will thus be observed that the piston moves between a point adjacent the port 47 and a point considerably spaced from the open end of the cylinder so that a lubricating chamber 49 is formed at this end. From this lubricating chamber leads a lubrication port 50 which opens through the flat side of the cylinder and ensures lubrication of the joint between the said cylinder and the plate 37. Also a relief port 51 is provided at this end 110

of the cylinder so that the piston 48 may be free in the cylinder. This lubricant chamber is closed by a cylinder head 52 and a piston rod 53 extends from the piston 48 through this head, being provided with an end 54 fitting on a crank pin 55 carried by a crank disc 56. This crank disc is supported on a shaft 57 driven from any suitable source of power, but preferably from the 10 cam shaft of the engine to which the carburetor is connected.

In operation the action of the pump produces a series of vacuum impulses in the chamber to which the conduit 30 leads.

15 This, of course, effects lifting of the fuel from the fuel tank. Now consider the construction shown in Figure 1; it will be seen that after a definite amount of fuel has been drawn into the fuel receiving chamber, the 20 float 33 will lift and close the valve 24 thus freeing this chamber from the vacuum effect. Now by reason of the horizontal arrangement of the valve 19 the fuel will act under gravity to open this valve and pass 25 down in to the chamber 10. When the float has dropped on to the collar 22 the valve 24 will open and the renewed vacuum in the upper chamber will close the valve 19.

It is most particularly noted that without 30 the provision of a relief valve between the valve 24 and the suction producing means, this valve 24 would fail to operate and the device would thus be rendered inoperative for any effective purpose. With the use of 35 a relief valve this difficulty is overcome and moreover, this valve may be adjusted in the usual manner so that precisely the desired degree of even vacuum may be maintained at all times during operation.

40 There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within 50 the scope claimed.

Having thus described the invention, what is claimed as new, is:

1. The combination with a source of liquid fuel supply, of a carburetor, a fuel receiving 55 chamber communicating therewith, a conduit leading from the source of supply to the chamber, a source of suction entirely independent of the carburetor but connected to the chamber, and a relief valve interposed 60 between the source of suction and the chamber, whereby an intermittent vacuum is ob-

tained the maximum of which is substantially constant in said chamber independent of the pressure in the carburetor.

2. The combination with a source of liquid fuel supply, of a carburetor, a fuel receiving chamber communicating therewith, a conduit leading from the source of supply to the chamber, a suction pump entirely independent of the carburetor but connected 70 to the chamber, and a relief valve interposed between the suction pump and the chamber, whereby an intermittent vacuum is obtained the maximum of which is substantially constant in said chamber independent of the pressure in the carburetor. 75

3. The combination with a source of liquid fuel supply, of a carburetor, a fuel receiving chamber communicating therewith, a conduit leading from the source of supply to the chamber, a suction pump entirely independent of the carburetor, a second conduit connecting the suction pump and the chamber, a valve arranged to close the second conduit when the fuel in the chamber reaches 80 a predetermined height, and a relief valve in the second conduit, whereby an intermittent vacuum is obtained the maximum of which is substantially constant in said chamber independent of the pressure in the carburetor. 85

4. The combination with a source of liquid fuel supply, of a carburetor, a fuel receiving chamber, a valve controlling communication between the fuel receiving chamber and the carburetor, a conduit leading from the source of supply to the chamber, a suction pump entirely independent of the carburetor, a second conduit connecting the suction pump and the chamber, a valve arranged to close the second 100 conduit when the fuel in the chamber reaches a predetermined height, and a relief valve in the second conduit, whereby an intermittent vacuum is obtained the maximum of which is substantially constant in said chamber independent of the pressure in the carburetor. 95

5. The combination with a source of liquid fuel supply, of a carburetor, a fuel receiving chamber communicating therewith, a conduit leading from the source of supply to the chamber, a source of suction entirely independent of the carburetor, a second conduit connecting the source of suction to the chamber, and a relief valve connected to said 110 second conduit and controlled by the source of suction, whereby an intermittent vacuum is obtained the maximum of which is substantially constant in said chamber independent of the pressure in the carburetor. 115

120 In testimony whereof I affix my signature.
FLOYD F. FLINT.
